UNITED STATES PATENT OFFICE.

JAMES ALEXANDER MOORE, OF WEIR CITY, KANSAS, ASSIGNOR OF ONE-HALF TO H. ALLEN, OF SAME PLACE.

CRUTCH.

SPECIFICATION forming part of Letters Patent No. 683,568, dated October 1, 1901.

Application filed June 25, 1901. Serial No. 65,979. (No model.)

To all whom it may concern:

Be it known that I, JAMES ALEXANDER MOORE, a citizen of the United States, residing at Weir City, in the county of Cherokee and

5 State of Kansas, have invented a new and useful Crutch, of which the following is a specification.

This invention relates to crutches; and the object of the same is to provide a simple, durable, and economical crutch by utilizing certain improved means whereby the jar and impact caused by coming into contact with the pavement or the like will be reduced to a minimum.

15 The invention consists in the construction and arrangement of the several parts, which will be more fully hereinafter described and claimed.

In the drawings, Figure 1 is a perspective view of a crutch embodying the features of the invention and shown broken through in part. Fig. 2 is an enlarged sectional elevation of a portion of the crutch. Figs. 3 and 4 are detail perspective views of portions of 25 the crutch.

Similar numerals of reference are employed to indicate corresponding parts in the several views.

The numeral 1 designates the opposite side 30 members of the upper body portion of the crutch and have their upper terminals connected by an arm-rest 2, and at a lower point supplied with a grip-brace 3. The lower ends of the side members are reduced and secured in the upper terminals of upwardly-divergent arms 4 of an intermediate support 5, the latter also having a vertically-extending tubular guide 6 between the arms 4, which communicates with a lower central socket 7 35 in said support. The staff 8 has an upper reduced stem 9 slidably mounted in the socket 7 and guide 6 and between a shoulder 10 at the lower termination of the stem and the upper end of the said socket, the latter 40 being of greater diameter than the bore of the guide, and surrounding the said stem is a spring 11, which permits the upper portion of the crutch, including the support, to yieldingly slide on the stem with a cushion effect, 45 the said stem being of such length as to permit considerable vertical movement thereon. The upper end of the stem is provided with

a cap-nut 12, which is held in place by a screw-thread joint, to thereby prevent the said stem from becoming detached from the 55 support.

The lower end of the staff 8 is adjustably mounted in a tubular footpiece or socket 14, the adjustment being maintained by a set-screw 15, and on the lower ends of the said 60 piece or socket is a rubber or other suitable tip or cushion 16. By means of the tubular footpiece or socket 14 the clutch may be lengthened or shortened to suit different persons.

65 The intermediate support 5 not only provides a strong and durable structure, but at the same time a simple mode of providing a cushioned effect is obtained.

The parts of the improved crutch are easily 70 assembled, and in view of the adjustable feature set forth a convenience of material importance in this class of devices results.

Having thus described the invention, what is claimed as new is—

75 1. In a crutch, the combination of an upper body portion including side members, an intermediate support having upwardly-divergent side arms in which the lower ends of said side members are rigidly secured, and a 80 spring-actuated staff having its upper extremity movably mounted in the central portion of the said support between the divergent side arms of the latter, the staff having means in connection therewith for lengthening or shortening the same.

2. In a crutch, the combination of an upper body portion including side members, an intermediate support having upwardly-divergent side arms to which the said body portion is secured, the support also having a 90 central vertically-extending guide of tubular form, and a lower socket communicating with said guide, a staff having an upper reduced stem movably mounted in the socket and 95 guide, and a spring surrounding the stem and fitting in the socket.

In testimony that I claim the foregoing as my own I have hereto affixed my signature in the presence of two witnesses.

JAMES ALEXANDER MOORE.
